(57) **CLAIM**

The ornamental design for a medical awareness sleeve, as shown and described.

DESCRIPTION

FIG. 1 is a perspective view of a medical awareness sleeve showing my new design in its expanded, usable condition.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1.

FIG. 8 is a perspective view similar to FIG. 1 showing my new design in its collapsed condition.

FIG. 9 is a front elevational view of FIG. 8.

FIG. 10 is a left side elevational view of FIG. 8, the right side elevational view being a mirror image thereof; and,

FIG. 11 is a top plan view of FIG. 8, the bottom plan view being a mirror image thereof.
